UNITED STATES PATENT OFFICE.

CHARLES A. MYERS, OF NIAGARA FALLS, NEW YORK.

STREET AND STATION INDICATOR.

No. 870,737.

Specification of Letters Patent.

Patented Nov. 12, 1907.

Application filed November 8, 1906. Serial No. 342,542.

To all whom it may concern:

Be it known that I, CHARLES A. MYERS, a citizen of the United States, residing at Niagara Falls, in the county of Niagara and State of New York, have invented certain new and useful Improvements in Street and Station Indicators; and I do declare the following to be a full, clear, and exact description of the invention, such as will enable others skilled in the art to which it appertains to make and use the same.

10 My invention is an improved street and station indicator for electric railway cars, and it consists in the construction, combination and arrangement of devices hereinafter described and claimed.

In the accompanying drawings,—Figure 1 is an elevation of a street and station indicator embodying my improvements; Fig. 2 is a transverse sectional view of the same; Fig. 3 is a detail view of the detent for locking one of the operating armatures in inoperative position, and releasing the other armature so 20 that it may be operated by the electro-magnet; Fig. 4 is a detail elevation showing one of the dogs and its coacting spring; and Fig. 5 is a detail perspective view of the electric circuit closer for obtaining current from the trolley wire for operating the indicator.

25 The casing 1, which incloses the indicating mechanism may be of any suitable form and is provided in its front side with a glazed opening 2, through which the names of the streets or stations on the apron 3 are successively exposed by the movement of said apron.

30 This apron is made of thin sheet steel or other metal, is elastic and constitutes a spring which when released will coil upon itself. The said apron is provided near its side edges with openings 4 to receive operating studs 5, which project from a pair of rollers 6. Said 35 rollers have their shafts 7 mounted in bearings in the ends of the casing and are disposed near the front of the casing and are spaced apart so that the intermediate portion of the apron is stretched between them and maintained in a straight line, as shown in Fig. 2.

40 The end portions of the apron extend into cylindrical casings 8 through openings 9 in said casings, and the ends of the said apron coil upon themselves so that they become compactly disposed in said cylindrical casings. As the apron is moved in either direction 45 by the rotation of the rollers 6, one end of the same will become coiled in one of the casings 8, while the other end will become uncoiled in the other casing 8, as will be readily understood. Said casings 8 are connected together by bars 10, and are provided at

50 their ends with radially-disposed ears 11, which bear against the ends of the casing 1, and are secured thereto by screws, studs or other suitable devices indicated at 12. The cylindrical casings 8 are provided with slide covers 13, which operate in guides 14, and may be moved in one direction to widen the respective areas of the openings 9 to permit the insertion of the

coiled ends of the apron in said casings or their removal therefrom, and may be moved in the opposite direction to nearly close said openings and serve as guides for the apron. The said slide covers have 60 their outer ends extended, as at 15, and attached to rods 16. Said rods may be seated or unseated from openings 17 in the ends of the casing 1, and when seated in said openings may be secured therein by means of turn-buttons, or other suitable devices 18. 65 On one end of each roller shaft 7 is a pinion 19, fixed thereto to rotate therewith.

A gear 20, which is mounted on a shaft 21 engages the pinions 19 and on the outer side of the said gear 20 is secured a ratchet wheel 22.

70 A pair of rock-arms 23 are pivotally-mounted on the shaft 21 and extend in opposite directions therefrom. The said rock-arms carry dogs 24 to engage opposite sides of the ratchet wheel 22. The said dogs are provided with cam faces 25, 26, and the said rock-arms 75 carry springs 27, the free ends of which bear against the cam faces 25 or 26 of the dogs. When the spring bears against the cam face 25 of one of the dogs, said dog will be maintained in engagement with one side of the ratchet wheel 22. The dog on the opposite side 80 of said ratchet wheel must be set out of engagement with said ratchet wheel, and will be held in such position by its spring 27, which will bear against its cam face 26. Levers 28 are here shown as fulcrumed at 29 and as connected to the rock-arms 23 by links 30. 85 Springs 31 are here shown as connected to the rock-arms to move them together with the dogs which they carry in one direction. To each of the levers 28 is connected an armature 32, and springs 33 are here shown connected to the said armatures, which springs coact 90 with the springs 31.

95 It will be understood that the springs 31 or the springs 33 may be dispensed with, but I here show both sets of said springs for the purposes of this specification. The springs 33 in the form of my invention here shown, not only serve to coact with the springs 31, but also serve to direct the movement of the armatures to facilitate the operation thereof. The armatures may be operated by an electro-magnet 34, which is here shown as supported on one side of the casing 1 100 in operative relation to the armatures by means of a bracket 35. The electro-magnet may be supported by any suitable means and I do not limit myself in this particular. A detent device, which is here shown as a slide 36, operating in guides 37 on the rear side of the 105 casing 1, is employed for locking one of the armatures against operation, while releasing the other armature, so that it may be operated by the electro-magnet. The said slide has openings 38 to clear the armatures and when the slide is moved in position to 110 clear one of the armatures and permit its operation, it is disposed in the path of the other armature to prevent

the operation thereof, as shown in Fig. 1. The electro-magnet is momentarily energized just after leaving each street or station by means of a circuit-maker and breaker, which coacts with a trolley wire to supply current to the electro-magnet.

In Fig. 5, a portion of the trolley wire is indicated at 39 and is provided with a contact device 40, which extends to one side thereof. The trolley pole 41 in addition to carrying the trolley wheel 42 is also provided with the contact device 43, disposed to one side of the trolley wheel and which is insulated from the trolley pole and as it passes the contact device 40 momentarily engages the latter to send a current through the electro-magnet, and cause the latter to operate 15 one of the armatures.

The action of the armature imparted thereto by the electro-magnet causes the lever 28 connected to said armature and the link-rod 30 to move the rock-arm 23 connected to said link-rod against the tension of the 20 springs 31, 33, so that said rock-arm draws its dog 24 idly on the ratchet wheel 22 without imparting movement to said ratchet wheel. The instant that the electro-magnet becomes deenergized, the springs 31, 33, return the armature, its lever 28, link rod 30, and 25 rock-arm 23 to their normal positions, and such movement of the rock-arm 23 causes its dog 24 which is in engagement with the ratchet wheel 22 to impart a partial rotation to said ratchet wheel, as will be understood. This movement of the ratchet wheel causes 30 the gear 20 to turn therewith and said gear being in engagement with the pinions 19, which are connected to the rollers 6, said rollers are turned a sufficient distance to move the apron 3 so as to display the name of the next street or station through the opening 2. 35 It will be understood that after reaching the end of the line and before making the return run, the detent device 36 must be set so as to cause the last-operated armature to be locked and to release the other armature. The dog which is connected to the inoperative armature must be also set in the position shown in Fig. 4, 40 out of engagement with the ratchet wheel 22.

To check the movement of the rock-arms 23, which carry the operating dogs, I provide cylinders 44 and dashers or pistons 45. The said cylinders are secured 45 on the casing 1 and each is open at one end. The pistons or dashers are attached to the rock-arms, and as the rock-arms move by the action of the springs, said pistons or dashers enter said cylinders, compress the air therein and serve to cushion the rock-arms and to 50 check the movement thereof, as will be understood. To enable the rollers 6 to be turned manually in adjusting the apron, I provide a knob 46, which is indicated in a dotted circle in Fig. 1. Said knob is at-

tached to the shaft 21 to which the gear 20 and ratchet wheel 22 are secured and which turns with said gear 55 and ratchet wheel.

From the foregoing description, taken in connection with the accompanying drawings, the construction and operation of the invention will be readily understood without requiring a more extended explanation. 60

Various changes in the form, proportion, and the minor details of construction may be resorted to without departing from the principle or sacrificing any of the advantages of the invention, as defined by the appended claims. 65

Having thus described my invention, what I claim as new, and desire to secure by Letters-Patent, is,—

1. In combination with the driving element of a station indicator, an electro-magnet, independently-operated armatures, means actuated by the respective armatures and coacting with the driving element to move the latter in reverse directions, and means to lock either of the armatures against movement and release the other for movement by the electro-magnet, substantially as described. 70

2. In combination with the driving gear of a station indicator and a ratchet wheel revolvable with said gear, rocking arms having pawls to engage opposite sides of the ratchet wheel, an electro-magnet, independently-operated armatures connected to the respective rocking arms to actuate the latter, and means to lock either of the armatures against movement and release the other for movement by the electro-magnet, substantially as described. 80

3. In combination with the driving gear of a station indicator and a ratchet wheel revolvable with said gear, rocking arms having pawls to engage opposite sides of the ratchet wheel, an electro-magnet, independently-operated armatures connected to the respective rocking arms to move the latter in one direction, springs to move said rocking arms in the reverse direction, and means to lock either of the armatures against movement and release the other for movement by the electro-magnet, substantially as described. 85

4. In combination with the driving gear of a station indicator and a ratchet wheel revolvable with said gear, rocking arms having pawls to engage opposite sides of the ratchet wheel, an electro-magnet, independently-operated armatures connected to the respective rocking arms to move the latter in one direction, springs to move said rocking arms in the reverse direction, means to lock either of the armatures against movement and release the other for movement by the electro-magnet, plungers carried by said rocking arms, and fixed cylinders, each open at one end for the reception of one of said plungers to cushion the strokes of said rocking arms, substantially as described. 95

In testimony whereof I have hereunto set my hand in presence of two subscribing witnesses.

CHARLES A. MYERS.
